SNAP-ACTING SWITCH

John A. Spencer, Newtonville, Mass., assignor to
General Plate Company, Attleboro, Mass., a corpora-
tion of Massachusetts

Application April 4, 1932, Serial No. 602,909

11 Claims. (Cl. 200—138)

This invention relates to electrical switches, and with regard to certain more specific features, to electrical switches of snap-acting character.

Among the several objects of the invention may be noted the provision of a snap-acting electrical switch which has an increased amount of displacement between its two positions; a snap-acting switch of the class described which is radially corrugated and which is provided with means for effecting a more accelerated snap action; and the provision of a snap-acting switch, constituting in one embodiment a thermostatic switch, which is economical in manufacture and simple and positive in action. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawing, in which is illustrated several of various possible embodiments of the invention,

Fig. 1 is a plan view of a snap-acting switch embodying the invention;

Fig. 2 is a cross-section taken substantially on line 2—2 of Fig. 1; and,

Fig. 3 is a cross-section taken substantially on line 3—3 of Fig. 1.

Similar reference characters indicate corresponding parts throughout the several views of the drawing.

In my Patent No. 1,895,590, dated January 31, 1933, for Snap-acting devices (application for which was filed July 26, 1930, and which was thus copending herewith), I have shown an improved form of snap-acting device which includes as a feature, radial corrugations, whereby an increased amount of resilient material is present in the region where displacements take place under change from one to another position. The present invention comprises an electric switch including a thermostat which is an improvement over the radially corrugated device illustrated in said copending application. The invention will be described principally by reference to its thermostatic embodiment, that is, where it performs in response to temperature changes. However, it will be understood that, even as a thermostat, the invention is fundamentally a snap-acting device.

Referring now more particularly to Fig. 1, there is illustrated at numeral 1, the interior, dished

or cup or concave radially corrugated region comprising the operative portion of a thermostatic embodiment of the present invention. This portion 1 is preferably formed from a seamless cylinder of composite thermostatic metal in the manner set forth in said copending application, which comprises, briefly, longitudinally corrugating a cylinder of thermostatic metal and constricting said corrugated cylinder at one end as well as compressing it longitudinally until substantially a truncated cone or dished disc is obtained.

The term "composite thermostatic metal" is used herein to define a material composed of materials having relatively different coefficients of thermal expansion. This type of thermostat is frequently termed "bimetallic". The principle upon which the thermostat operates is that, under varying conditions of hot and cold, one layer of the composite metal will exhibit a relatively greater or less tendency to expand than the other layer, and thereby build up a stress in the body which the two metals form.

The stress thus set up grows with increased temperature until strains are effected whereby the disc reverses curvature with a snap. That is, if the disc or dish or the like was originally concave, relative to its original conformation it becomes convex, or vice versa.

The radial corrugations in the present thermostat, as in the thermostat of said copending application, are advantageous in that they provide an increased amount of thermostatic metal in the central portion of said disc, and, when the thermostat is brought to a condition in which it is about to snap, it effects an increase in the amount of displacement through which the center of the thermostat operates. This increased displacement is highly advantageous when the thermostat is utilized, for example, in electrical equipment, for making and breaking electrical contacts.

The present invention contemplates the formation of a radially corrugated disc such as illustrated in my copending application, and the provision thereon of a substantially flat, or uncorrugated rim or circumferential portion 3. A thermostat produced according to the present invention has the following advantages:

First, the inherent tendency of the thermostat to expand radially, and thereby to decrease its kinematic efficiency, is limited and controlled by the relatively non-expansile rim or confining portion 3. That is, with thermostats of the type shown in said copending application, there is a

110

tendency upon heating for straightening of the sinuous edge, with the result that the constrictive function of the periphery is reduced as snap action occurs. Hence the thermostat functions 5 more sluggishly than if the edge were to maintain a more constant restrictive characteristic. The flat rim portion 3 of the present invention, having no corrugations therein, has substantially no tendency to stretch, and it accordingly better 10 serves as a restricting or confining or binding means for the remainder of the thermostat. That is to say, there are no undulations in the periphery to provide resiliency.

The thermostatic element as thus described is 15 provided with certain adjunctive elements for converting it into an electric switch. As shown in the present drawing, these adjunctive elements are analogous to those shown in my Patent No. 1,718,716, dated June 25, 1929, and comprise 20 a bottom supporting plate 12, and a top supporting plate 13, each having a central aperture therethrough, within which there is located a tubular clamping member 14. The clamping member 14 is provided with an annular shoulder at the bottom 25 thereof and is made substantially longer than the combined thickness of the two plates 12 and 13, to secure the two plates in proper operative position in face to face relation. The periphery of the upper end of the tubular member 14 is 30 compressed to provide an annular portion 15 overhanging the top plate 13.

The plate 12 is provided with a plurality of spaced openings 16, and the plate 13 is provided with a plurality of spaced openings 17, the openings 35 17 being coaxial with the openings 16, and of smaller diameter. (See Fig. 3).

A plurality of contact plates 27, 28, 29 and 31 are operatively supported by the supporting plate assembly and are located against the outer surface 40 of the insulating member 18. The contact plates 27 to 31, inclusive, are of substantially arcuate shape.

Means for securing the respective contact plates against the supporting plate and the insulating-plate assembly, as shown in Fig. 3, comprises 45 rivet members 32 having an enlarged head 33, and extending through the respective coaxial openings 16 and 17 in the plates 12 and 13, a disc 34 of electric insulating material, such as mica, serving 50 to insulate the head 33 from the plate 13, and serving also to position the body of the rivet 32 in the opening 17 and to maintain it coaxial therewith. This construction is more particularly shown in Fig. 3 in the drawing.

55 The cooperating, or circuit completing contacts are mounted on the broad, flat rim portion 3 of the thermostatic disc 1. The disc 1 is adjustably mounted in substantially parallel-spaced relation to the supporting plate assembly. This 60 mounting comprises a shouldered screw-threaded stud 36 that projects through the internally screw-threaded tubular clamping member 14 and that has a flanged member 37 located close to one end thereof. A nut 38 is provided adjacent to, 65 but spaced from, the flange 37, and the disc 1 is loosely mounted between the nut 38 and flange 37 to permit of a turning movement of the stud relatively to the internally screw threaded tubular member 14 to permit of varying the distance of 70 the thermostatic disc and of other members carried thereby toward and away from the contact plates hereinbefore described.

The end of the stud 36 is provided with a portion 39 of reduced thickness that may be made 75 of substantially rectangular form in section, in

order to permit of holding the stud 36 while a lock-nut 41 is tightened to prevent any further turning movement of the stud 36 after proper adjustment has once been made.

A plurality of contact bridging members 42 are supported by the thermostatic disc 1, by means of a stud member 43. The construction of the members 42 is adequately described in said Patent 1,718,716, and requires no particularization herein.

To align the disc and base members, a stud 53 is mounted in said base members and projects through an opening 55 in the rim 3 of the disc 1. The contacting members 42 are thus maintained in proper relationship to bridge the members 27, 28, 29, and 31 when the disc 1 snaps to contact-closing position.

It is to be understood that I am aware that a substantially flat rim has a slight capacity to stretch but it is to be noted that such capacity is much less than the corresponding capacity in an undulatory or sinuous rim. In the case of the flat rim the stretch effects only a tensile stress, whereas in the undulatory rim a bending moment is effective. My improvement comprises arranging the metal in the periphery so that it is not subjected to bending moments and hence is much more constrictive in its action. Hence the improved increased speed attained in the snap action.

It is to be understood that the invention refers to binding rims of the class set forth or analogous ones performing the same functions, as for instance independent binding rims, wires and the like. It also includes integral and other rims wherein the material is disposed not quite 105

flatly, but in such a manner that peripheral or lateral stretching at the outer ends of the radial or other corrugations is substantially reduced. For instance, the peripheral band 3 may have 110 stiffening bulges or indentations or the like which are independent of the radial corrugations. However, the form disclosed is preferable in the present embodiment.

A plurality of contact plates 27, 28, 29 and 31 are operatively supported by the supporting plate assembly and are located against the outer surface 40 of the insulating member 18. The contact plates 27 to 31, inclusive, are of substantially arcuate shape.

Means for securing the respective contact plates against the supporting plate and the insulating-plate assembly, as shown in Fig. 3, comprises rivet members 32 having an enlarged head 33, and extending through the respective coaxial openings 16 and 17 in the plates 12 and 13, a disc 34 of electric insulating material, such as mica, serving 45 to insulate the head 33 from the plate 13, and serving also to position the body of the rivet 32 in the opening 17 and to maintain it coaxial therewith. This construction is more particularly shown in Fig. 3 in the drawing.

The cooperating, or circuit completing contacts are mounted on the broad, flat rim portion 3 of the thermostatic disc 1. The disc 1 is adjustably mounted in substantially parallel-spaced relation to the supporting plate assembly. This 60 mounting comprises a shouldered screw-threaded stud 36 that projects through the internally screw-threaded tubular clamping member 14 and that has a flanged member 37 located close to one end thereof. A nut 38 is provided adjacent to, 65 but spaced from, the flange 37, and the disc 1 is loosely mounted between the nut 38 and flange 37 to permit of a turning movement of the stud relatively to the internally screw threaded tubular member 14 to permit of varying the distance of the thermostatic disc and of other members carried thereby toward and away from the contact plates hereinbefore described.

The end of the stud 36 is provided with a portion 39 of reduced thickness that may be made 70 of substantially rectangular form in section, in

order to permit of holding the stud 36 while a lock-nut 41 is tightened to prevent any further turning movement of the stud 36 after proper adjustment has once been made.

A plurality of contact bridging members 42 are supported by the thermostatic disc 1, by means of a stud member 43. The construction of the members 42 is adequately described in said Patent 1,718,716, and requires no particularization herein.

To align the disc and base members, a stud 53 is mounted in said base members and projects through an opening 55 in the rim 3 of the disc 1. The contacting members 42 are thus maintained in proper relationship to bridge the members 27, 28, 29, and 31 when the disc 1 snaps to contact-closing position.

It is to be understood that I am aware that a substantially flat rim has a slight capacity to stretch but it is to be noted that such capacity is much less than the corresponding capacity in an undulatory or sinuous rim. In the case of the flat rim the stretch effects only a tensile stress, whereas in the undulatory rim a bending moment is effective. My improvement comprises arranging the metal in the periphery so that it is not subjected to bending moments and hence is much more constrictive in its action. Hence the improved increased speed attained in the snap action.

It is to be understood that the invention refers to binding rims of the class set forth or analogous ones performing the same functions, as for instance independent binding rims, wires and the like. It also includes integral and other rims wherein the material is disposed not quite 105

flatly, but in such a manner that peripheral or lateral stretching at the outer ends of the radial or other corrugations is substantially reduced. For instance, the peripheral band 3 may have 110 stiffening bulges or indentations or the like which are independent of the radial corrugations. However, the form disclosed is preferable in the present embodiment.

3. In an electric switch, a thermostatic actuator comprising a sheet of composite thermostatic metal having corrugations therein, and means confining expansion along said corrugations, said 5 means carrying contacting buttons adapted to make and break electrical connections according to the relative position of said actuator.
4. In an electric switch, a thermostatic actuator comprising a disc of composite thermostatic metal, said disc having radial corrugations therein, and an uncorrugated rim portion on said disc, said rim portion carrying contacting buttons adapted to make and break electrical connections according to the relative position of said actuator.
- 10 5. An electric switch comprising a base member, terminal pieces arranged on said base member, a thermostatic actuator comprising a sheet of composite thermostatic metal having corrugations therein and formed to have two positions of 15 stable equilibrium, and having an uncorrugated confining rim portion, means mounting said actuator in spaced relationship to said base member, and one or more contacting buttons carried on said rim portion and positioned to complete an 20 electric circuit between said terminals on said base portion.
6. An electric switch comprising a base member, terminal pieces arranged on said base member, a thermostatic actuator comprising a disc of 25 composite thermostatic metal having radial corrugations therein and formed to have two positions of stable equilibrium, and having a peripheral, uncorrugated rim portion, means mounting said actuator in spaced relationship to said base member, and one or more contacting buttons carried on said rim portion and positioned to 30 complete an electric circuit between said terminals on said base portion.
7. An electric switch comprising a base member, terminal pieces arranged on said base member, a thermostatic actuator comprising a sheet of composite thermostatic metal having corrugations therein and formed to have two positions of stable equilibrium, means mounting said actuator in 35 spaced relationship to said base member, and one or more contacting buttons carried on said actuator and positioned to complete an electrical circuit between said terminals on said base portion.
- 40 8. An electric switch comprising a base mem- 50
- ber, terminal pieces arranged on said base member, a thermostatic actuator comprising a disc of composite thermostatic metal having radial corrugations therein and formed to have two positions of stable equilibrium, means mounting said actuator in spaced relationship to said base member, and one or more contacting buttons carried on said actuator and positioned to complete an electrical circuit between said terminals on said base portion.
- 45 9. In a snap-acting electric switch, a snap-acting actuator comprising a disc of resilient material having radial corrugations therein, the plane of the central portion of said disc being displaced from the plane of the peripheral portion thereof, the said disc being suitably resilient, whereby upon suitable actuation thereof, it overcenters to assume a position of opposite configuration, and electrical contacting means carried by said disc.
- 50 10. In a snap-acting electric switch, a snap-acting actuator comprising a disc of resilient material having radial corrugations therein, the plane of the central portion of said disc being displaced from the plane of the peripheral portion thereof, the said disc being suitably resilient, 100 whereby upon suitable actuation thereof, it overcenters to assume a position of opposite configuration, and means confining expansion along said corrugations, said means carrying electrical contacting means adapted to make and break electrical connections according to the relative position of said actuator.
- 55 11. An electric switch comprising a base member, at least one terminal piece arranged on said base member, a snap-acting actuator comprising 110 a disc of resilient material having radial corrugations therein, the plane of the central portion of said disc being displaced from the plane of the peripheral portion thereof, said disc being suitably resilient, whereby upon suitable actuation thereof, 115 it overcenters to assume a position of opposite configuration, means mounting said actuator in spaced relationship to said base member, and at least one electrical contacting means carried on said actuator and positioned to cooperate with the terminal piece on said base member to control an electrical circuit.
